UNITED STATES PATENT OFFICE

91,171

DESIGN FOR A VALVE LEVER

Archibald R. Lemieux, Worcester, Mass.

Application July 17, 1933. Serial No. 48,742

Term of patent 3½ years

To all whom it may concern:

Be it known that I, ARCHIBALD R. LEMIEUX, a citizen of the United States, residing at Worcester, in the county of Worcester and State of Massachusetts, have invented a new, original, and ornamental Design for a Valve Lever, of which the following is a specification, reference being had to the accompanying drawing forming part thereof.

Fig. 1 is a side view of the article showing my new design;

Fig. 2 is an edge view;

Fig. 3 is a plan, and

Fig. 4 is a perspective view thereof on a reduced scale.

I claim:

The ornamental design for a valve lever as shown.

ARCHIBALD R. LEMIEUX.
